UNITED STATES PATENT OFFICE.

THOMAS K. KEITH, OF BOSTON, MASSACHUSETTS, ASSIGNOR TO TONGUE
LOCK SEWING MACHINE COMPANY, A CORPORATION OF MAINE.

SHOE-SEWING MACHINE.

SPECIFICATION forming part of Letters Patent No. 700,693, dated May 20, 1902.

Application filed October 1, 1901. Serial No. 77,218. (No model.)

To all whom it may concern:

Be it known that I, THOMAS K. KEITH, of Boston, in the county of Suffolk and State of Massachusetts, have invented certain new and useful Improvements in Boot and Shoe Sewing Machines, of which the following is a specification.

This invention relates to machines for securing the upper to the sole of a boot or shoe by loops from a single thread drawn through the upper and through the portion of the sole usually known as the "between substance," the bights of the loops being drawn over and locked by tongues cut in one side of the sole. The present invention relates particularly to machines of this character employing loop-forming mechanism, which includes an oscillating needle adapted to draw a loop of thread through the upper and the between substance and to hold it temporarily over the sole before the operation of taking up the loop; and it has for its object to provide improved means for spreading the loop prior to and during the taking-up operation, and thus insuring the proper engagement of the loop with a tongue cut in the sole, the loop being drawn down and tightened across the tongue by the operation of the take-up mechanism.

The invention consists in the improved loop spreading and controlling mechanism hereinafter described and claimed.

Of the accompanying drawings, forming a part of this specification, Figure 1 represents an end elevation showing my improved loop spreading and controlling mechanism in connection with certain other parts of the machine, the loop-spreader being shown in its depressed position and bearing upon the outer surface of the sole. Fig. 2 represents a view similar to Fig. 1, showing the loop-spreader raised and retracted and the needle projected. Fig. 3 represents a view similar to a portion of Fig. 2, showing the needle retracted and holding the loop over the sole and the loop-spreader advanced into the loop. Fig. 4 represents a perspective view showing the loop-spreader and needle in the position shown in Fig. 3. Fig. 5 represents a fragmentary view looking downwardly upon the sole of the shoe and showing the members of the loop-spreader in the positions represented in Fig. 1. Fig.

6 represents a section on line 6.6 of Fig. 1, and Fig. 7 represents a section on line 7.7 of Fig. 1.

The same numerals of reference indicate the same parts in all the figures.

In the drawings, 1 represents the oscillating curved needle, the carrier 2 of which is pivoted at 3 to the frame of the machine and may be oscillated by any suitable means. 60 The machine is equipped with suitable instrumentalities coöperating with the needle, whereby the needle is enabled to draw a loop 5 from a single thread through the upper 7 and through the between substance of the sole 65 70 of a boot or shoe, each loop being drawn through the between substance under a tongue 8, cut in the outer surface of the sole, as shown in Fig. 4, and subsequently taken up, so that its neck portion 50 extends across 70 the said tongue and is locked thereby, as shown in Figs. 4 and 5. Since my invention relates only to the means for spreading and controlling the loop while it is being taken up, I have not deemed it necessary to show 75 and describe the said coöperating instrumentalities. The said loop spreading and controlling mechanism comprises a spreader adapted to enter the loop 5 while the latter is held by the needle and composed of two 80 arms or members 9 9, which are movable laterally toward and from each other to contract the spreader, as shown in Fig. 4, and to expand it, as shown in Fig. 5, the spreader being adapted when in its contracted condition to separate or spread the side portions of the loop and to support or control the loop in such manner as to insure the proper engagement of its neck portion 50 with the accompanying tongue 8. The spreader members 85 are formed on the lower ends of levers 10 10, which are fulcrumed at 12 12 to the lower end of a carrier-arm 13. Said arm is pivoted at 14 to one arm of a bell-crank lever 15, which is fulcrumed at 16 on the frame. 90 The other arm of the bell-crank lever 15 has a cam-shaped slot 17, which receives a stud 18 on an operating-lever 19. The lever 19 is fulcrumed at 20 on the frame and has at its outer end a stud 21, which enters a cam-shaped slot 22 in the carrier-arm 13. The outer end of the operating-lever 19 has a 95 100

trundle-roll 23, which enters a cam-groove 24 in a disk on the shaft 25, the operating-lever being oscillated by the rotation of said shaft. The oscillating movements of the lever 19 5 cause the stud 18 and the walls of the cam-shaped slot 17 to oscillate the bell-crank lever 15, which in turn vertically reciprocates the carrier-arm 13 and the spreader members 9 9, the latter being thus moved toward 10 and from the sole. The stud 21 and the walls of the cam-shaped slot 22 cause the carrier-arm to oscillate during its vertical movements, its oscillations causing it to enter and leave the loop.

15 The spreader-operating means thus far described move the spreader bodily toward and from the sole and into and out of the loop. I have also provided means for moving the spreader members laterally in opposite directions, thus alternately expanding and contracting the spreader, said means comprising studs 26 26, formed on the lower ends of arms 27 27, which are pivoted at 28 to the lever 19 and cam-shaped slots 29 29 in the levers 10 10, 20 said slots receiving the studs 26. The arms 27 are provided with slots 30, which receive studs 31, affixed to the bell-crank lever 15, 25 said slots and studs confining the arms 27 and studs 26 against loose oscillating movement 30 on the studs 28.

The operation is as follows: When the needle has drawn a loop 5 through the upper and the between substance and stands in the position shown in Figs. 3 and 4, the spreader 35 is contracted and its members 9 9 are raised and retracted, their pointed forward ends being close together and in position to enter the loop at a point between the needle and the sole. The spreader while contracted moves 40 forward into the loop and is then moved downwardly and during its downward movement is expanded, so that when it bears upon the sole its members 9 9 are well separated and are at opposite sides of the tongue 8, under 45 which the loop was drawn, as shown in Fig. 5. The loop is disengaged from the needle by suitable cast - off mechanism after the spreader has entered it, and after the spreader members reach the position shown in Figs. 1

and 5 the take-up mechanism pulls in the 50 slack of the loop and draws the neck 50 of the loop down upon the tongue 8, the spreader members being moved backwardly out of the loop before the loop has been entirely taken up. The spreader is afterward raised to the 55 position shown in Fig. 2 and is contracted during its upward movement. It will be seen that the expansion of the spreader after it enters the loop, so that its members bear on the sole at opposite sides of the tongue, causes 60 a portion of the loop to extend across the tongue 8 and to a considerable distance at each side of the tongue, so that there is no liability of failure of the neck of the loop to properly engage and be locked by the tongue. 65 Hence any slight bending or displacement of the tongue to one side or the other of its intended position (which displacement is liable to occur) does not prevent the tongue from properly engaging the neck of the loop. 70

I do not limit myself to the details of mechanism here shown and described for moving the spreader bodily and for expanding and contracting it, as these details may be variously modified without departing from the 75 spirit of my invention.

I claim—

A machine of the character specified comprising loop-forming mechanism including an oscillating hooked needle adapted to draw a 80 loop through an upper and through the "between substance" of a sole, and hold the loop over the sole, a loop-spreader composed of two members which are movable laterally in opposite directions to expand and contract 85 the spreader, and spreader-operating mechanism having provisions for moving the spreader as a whole to cause it to enter and recede from the loop and move toward and from the sole, and for moving the said members laterally to expand and contract the spreader, substantially as described. 90

In testimony whereof I have affixed my signature in presence of two witnesses.

THOMAS K. KEITH.
